UNITED STATES PATENT OFFICE

117,269

DESIGN FOR A FLASHLIGHT

Leopold C. Grimsley, New York, N. Y., assignor to Henry Hyman, Brooklyn, N. Y.

Application September 16, 1938, Serial No. 79,938

Term of patent 14 years

To all whom it may concern:

Be it known that I, Leopold C. Grimsley, residing at New York, Queens County, State of New York, have invented a new, original, and ornamental Design for a Flashlight, of which the following is a specification, reference being had to the accompanying drawing, forming part thereof.

Fig. 1 is a side view of a flashlight, showing my new design, and

Fig. 2 is a side view at right angles to Fig. 1.

I claim:

The ornamental design for a flashlight, substantially as shown.

LEOPOLD C. GRIMSLEY.
